UNITED STATES PATENT OFFICE.

WALTER F. SPEAKMAN AND GUY E. CROCKETT, OF DRUMRIGHT, OKLAHOMA.

SECTIONAL-DERRICK-LEG CLAMP.

Application filed August 10, 1927. Serial No. 211,889.

This invention relates to a clamp for sectional derrick legs.

In our Letters Patent, No. 1,616,995, we have disclosed a type of clamp for use particularly with flanged leg sections.

We have now found that added advantages accrue if the shims forming part of the clamps are permanently secured to the ends of the leg sections. With this construction there is no danger of the shims being lost or falling down during construction of the derrick, nor is there any need for flanging the ends of the derrick leg sections. Furthermore, the ends of the leg sections are reinforced and the supporting strength of the legs greatly increased by providing the shims with full length flanges or wings, adapted to abut each other at their respective ends. The joints formed by securing an overlying flanged tubular member to said shims with the respective flanges positively interconnected throughout their entire lengths, are thus greatly strengthened.

It is therefore an object of this invention to provide an improved clamp construction for sectional derrick legs.

Other and further important objects of this invention will become apparent from the disclosures in the following description and appended claims.

In the accompanying drawings which illustrate a preferred embodiment of this invention and in which similar reference numerals refer to similar features in the different views:

Figure 1 is a side elevational view of a clamp for sectional derrick legs and connections thereto, with parts in section.

Figure 2 is a sectional view taken on line II-II of Figure 1 with parts removed.

Figure 3 is a sectional view taken on line III-III of Figure 1.

Figure 4 is a reduced sectional view taken on line IV-IV of Figure 1, with parts removed.

Figure 5 is a top plan view of the shims by themselves.

Figure 6 is a side elevational view of the clamp with one section of the outer tubular member removed and with parts in section.

As shown on the drawings:

The reference numeral 1 indicates a sectional derrick leg of tubular construction, such as is generally found in derrick structures. Said sectional derrick leg 1 comprises a plurality of sections having smooth abut-

ting edges 2. A sectional shim 3 is adapted to be mounted on the respective abutting ends of the leg sections and to be secured thereto by suitable means, as by pins or rivets 4. Each of said sectional shims 3 comprises a pair of curved sections 5 and 6 (Figure 5) together forming a cylinder, said sections having radially extending full length flanges, or wings, 7 and 8, respectively, at one of their longitudinal edges. Said flanges 7 and 8, as illustrated, are spaced apart by substantially 90° and accordingly, when the shims are in position on the ends of the derrick leg sections, said flanges point substantially in the direction of the other adjacent corner posts of the derrick, as will be apparent. It should be noted that the sections 5 and 6, when positioned in cylindrical form, do not quite meet but are spaced apart by longitudinal spaces 17. This is to allow for slight variations in the diameter of the legs.

It should further be noted that when the derrick leg sections are positioned in place, the adjacent ends of the flanges 7 and 8 of the respective shims form abutting supporting surfaces 20, which increase the normal bearing surface 2 between the leg sections themselves and thus increase the vertical load bearing capacity of the leg sections.

The other member of the clamp comprises an outer sectional tubular member 9 adapted to overlie the shims 3 on abutting leg sections and to be positively interconnected thereto. Said tubular member 9 comprises curved sections 10 and 11 (Figure 3) similar to the shim sections 5 and 6, but provided with flanges 12 and 13 at each of their respective ends. The flanges 8, of the shim section 6, lie between the flanges 12 and 13 of the tubular sections 10 and 11, respectively, and the shim flanges 7 lie between the other pair of tubular section flanges 12 and 13. A plurality of bolts 14 are adapted to extend through said adjacent flanges, thereby positively interconnecting the tubular member 9 with the shims 3. Girts and braces 15 are adapted to be secured to certain other bolts 16 passing through the adjacent flanges of the tubular member and shims.

It should be noted that in our present construction, the shims 3 are adapted to be permanently secured by means of the pins or rivets 4 to the ends of each of the leg sections, the heads of the rivets 4 being flush with the surface of the shims 3, and that said shims 3 terminate with the ends of said leg sections.

Accordingly, in setting up a derrick a sectional tubular member 9 is first attached to the shim 3 of a lower leg section by means of a bolt 14. In this position, said tubular member 9 forms a socket into which an upper leg section carrying a shim 3 may be dropped and bolted in place, by means of the upper bolt 14, through the respective flanges of the shim and tubular member sections. The full length flanges of the shims and tubular member not only greatly strengthen the joints of the sectional legs, but also serve for attaching the girts and braces 15. Furthermore, as pointed out above, the vertical load carrying capacity of the leg sections is greatly increased, owing to the additional contact surface 20 between the respective shim flanges 7 and 8.

We are aware that many changes may be made and numerous details of construction may be varied through a wide range without departing from the principles of this invention, and we, therefore, do not purpose limiting the patent granted hereon, otherwise than necessitated by the prior art.

25 We claim as our invention:

1. A sectional derrick leg shim, comprising curved members adapted together to form

a longitudinally divided cylinder and a flange on each of said members extending radially the full length of said shim members.

2. A combined clamp and connection for the leg sections, girts and braces of a sectional derrick, comprising a pair of sectional shims, each adapted to be secured to one end of abutting leg sections and having radially extending full length flanges, a sectional tubular member adapted to enclose said pair of shims and having cooperating radial flanges and fastening means for securing said flanges together and to said girts and braces.

3. A combined clamp and connection for the leg sections, girts and braces of a section derrick, comprising a pair of sectional shims, each adapted to be secured to one end of abutting leg sections and having radially extending full length flanges, the ends of said flanges terminating with the ends of said leg sections and thereby increasing the effective vertical load bearing surface of said leg sections.

In testimony whereof we have hereunto subscribed our names at Tulsa, Tulsa County, Oklahoma.

WALTER F. SPEAKMAN.
GUY E. CROCKETT.
